SUCTION NOZZLE

George Horace Cranmer, Philadelphia, Pa., assignor, by mesne assignments, to Electrolux Corporation, Dover, Del., a corporation of Delaware

Application January 22, 1935, Serial No. 2,873

12 Claims. (Cl. 15—157)

My invention relates to vacuum cleaners and more particularly to an improved suction nozzle for use with vacuum cleaners.

Depending upon the nature of the surface being cleaned and the nature of the dirt to be removed, it may be desirable to either draw the air through the surface, such as a rug, or to cause the air to pass rapidly over the surface as it enters the nozzle. If the dirt to be removed is imbedded in a rug or the like, it is preferable to have the edges of the nozzle form a comparatively tight seal with the surface so that the air drawn into the nozzle must pass chiefly through the rug, thereby dislodging and removing the dirt from within the rug. On the other hand, if the dirt lies chiefly on the surface to be cleaned, it may be better removed by providing a rapid flow of air along the surface. This may advantageously be done by providing grooves in the sealing edges 20 or lips of the nozzle through which the air will pass.

One of the objects of my invention is to provide a suction nozzle which may be readily altered so as to present either uninterrupted sealing edges to the surface or edges provided with grooves or channels therethrough.

Another object of my invention is to provide a nozzle of this nature which is quickly and easily alterable.

Still another object of my invention is to provide a structure for readily removing from rugs or other surfaces cotton threads or like matter tenaciously adhering thereto.

Further objects and advantages will be apparent from the following description considered in connection with the accompanying drawing of which:

Fig. 1 is an elevational view of a suction nozzle embodying my invention;

Fig. 2 is a bottom view of the nozzle shown in Fig. 1;

Fig. 3 is a bottom view on an enlarged scale of a portion of the nozzle as shown in Fig. 2;

Fig. 4 is a cross-sectional view taken on the line 4—4 of Fig. 3;

Fig. 5 is a cross-sectional view taken on the line 5—5 of Fig. 4;

Fig. 6 is a cross-sectional view taken on the line 6—6 of Fig. 4;

Fig. 7 is a cross-sectional view similar to Fig. 5, but with certain parts in a reversed position;

Fig. 8 is a cross-sectional view similar to Fig. 6, but with the parts reversed;

Fig. 9 is a cross-sectional view showing par-

ticularly locking means for maintaining the parts in the desired position; and

Fig. 10 is a perspective view of a member shown in Fig. 9.

Referring more particularly to Fig. 1, reference character 10 designates a nozzle mouthpiece which may be made of cast metal. A connection member 11 is secured to mouthpiece 10 and communicates with the interior thereof and is adapted to be connected to a conduit leading to a source of suction. This conduit usually comprises a rigid tubular member which also serves as a handle for moving the nozzle over the floor, and a flexible hose for connecting it to a vacuum cleaner unit.

Mouthpiece 10 may be described as comprising walls forming an elongated hollow member open at the bottom, the lower edges of the walls bounding the elongated suction opening 12. At both ends and at one side the edges are formed as sealing lips 13 which have lower faces adapted to contact the surface being cleaned. The other bounding edge 14 of the opening is formed with a semi-cylindrical groove 15, shown particularly in Figs. 5 to 8. The lip of side 14 includes a cylindrical rod 16 which is rotatably mounted in groove 15 and retained in place by means of screws 17 and 18 which are threaded into holes in the mouthpiece and which have round pivot portions extending into circular recesses 19 formed in either end of rod 16.

One side of rod 16 has a smooth semi-cylindrical surface 20, seen particularly in Figs. 6 and 8. The other side of the rod is formed with circular lugs 21 having a depth preferably less than $\frac{1}{2}$ the diameter of the rod. These lugs may be formed by slotting the rod in a direction at right angles to its length. Each lug is preferably made up of two parts 21a and 21b separated by a longitudinally extending groove 22, or it may be considered that there are two laterally disposed rows of laterally aligned lugs. Due to the fact that the lugs have a depth less than $\frac{1}{2}$ the diameter of the rod, the lugs will be entirely enclosed within the semi-circular groove 15 when in the position shown in Fig. 8. On the other hand, when the rod is turned through 180 degrees to the position shown in Fig. 6 the lugs will extend beyond the groove. The rod 16 is so positioned that its lower side is tangent to the plane of the other side or sealing lip of the suction opening or in horizontal alignment therewith.

One end of rod 16 is formed with a diametrically extending slot 23 within which is pivotally mounted a locking member 24. Member 24 may be piv-

oted about a rivet, pin or the like 25 which extends through or partly through the rod. As appears more clearly in Fig. 10 locking member 24 may consist of a piece of resilient material such as sheet steel which is bent back on itself around a small cylindrical member 35, thus forming a handle part 36. In unstressed condition the free ends 27 of member 24 tend to separate somewhat.

Adjacent locking member 24 the edge 14 of the mouthpiece is cut away slightly at 28 on either side of rod 16 sufficiently so that locking member 24 may project beyond either side of rod 16, as is shown in Fig. 3. With the locking member projecting in this manner, the rod 16 cannot be turned in either direction inasmuch as both the handle part 26 and one of the free ends 27 bear against the cut away surface 28. If it is desired to rotate rod 16 through 180 degrees, locking member 24 is pivoted slightly in a clockwise direction about rivet 25 from the position shown in Fig. 3 to that shown in Fig. 9. In the latter position the free ends 27 of member 24 do not extend outside of slot 23 formed in rod 16 and hence the rod may be rotated in a clockwise direction from the position shown in Fig. 6 to that shown in Fig. 8. Thereafter, if locking member 24 is pivoted slightly about rivet 25 so as to project the free ends 27 beyond the slot 23, the rod 16 will be again locked in position. Inasmuch as member 24 is resilient and the two sides tend to spring apart it has sufficient frictional engagement with the sides of slot 23 to hold it in whatever position it is placed.

The operation of the nozzle will be apparent from the preceding description. If it is desired to remove surface dirt from a rug, hardwood floor or any other kind of a surface, the rod 16 is placed in the position shown in Figs. 2, 4, and 6, that is, with the lugs 21 extending downwardly. When the pressure within the mouthpiece is reduced, atmospheric air will pass rapidly through the grooves between the lugs and will pick up surface dirt and carry it to the vacuum cleaner unit. Movement of the nozzle over the surface being cleaned causes the lugs 21 to dislodge dirt clinging to the surface and these lugs are more effective for this purpose than is a smooth lip, such as 13. Also, the longitudinal slot 22 dividing the lugs into two parts provides edges 30 which aid in the dislodgment of surface dirt. It will be seen that the remote outer surfaces or faces of the lugs are curved in a manner which may be termed convexly rounded and the lugs are so arranged that, on forward or backward movement of the nozzle, the lugs having rounded faces forward act as guards with respect to the straight faces or edges 30 of the following lugs. Moreover, the transverse grooves and the longitudinal slot cause turbulence of the air which results in a better dislodgment of the dirt.

If, on the other hand, it is desired to remove dirt which is embedded in a rug or the like, rod 16 is turned to the position shown in Fig. 8 where a smooth surface is presented to the rug. This surface, in conjunction with lips 13, provides a seal between the nozzle and the rug with the result that a large proportion of the air drawn into the nozzle passes through the rug, thereby dislodging imbedded dirt and carrying it to the vacuum cleaner unit. Due to the closeness of the surface of cylindrical rod 16 to the recess surface, essentially no air can pass between the relatively rotatable parts.

When being used to clean certain rugs having a close weave which offers a high resistance to the passage of air therethrough, an ordinary nozzle

with smooth sealing lips may have such a high suction developed therein as to interfere with movement of the nozzle over the surface. If this occurs with the present nozzle, rod 16 may be turned so that lugs 21 protrude. The air passing between the lugs reduces the suction and permits the nozzle to be moved more easily.

It is obvious that, if desired, two rods similar to rod 16 may be placed on either side of suction opening 12. While I have shown one embodiment of my invention it is to be understood that this has been done for purposes of illustration only and that modifications thereof fall within its scope which is to be determined by the appended claims viewed in the light of the prior art.

What I claim is:

1. A surface engaging lip structure for a suction cleaner nozzle, the surface contacting portion of said lip structure including relatively rotatable parts, having at least two different operative positions, and presenting nap engaging surfaces of different contours in said positions.

2. Apparatus as set forth in claim 1 in which the lip structure is formed with a groove of part-cylindrical contour and includes a rotatable part 26 of generally cylindrical form movable in said groove with the surfaces of the relatively movable parts so close as to prevent substantial air leakage therebetween.

3. Structure as set forth in claim 1 in which the different contour surfaces are on the same rotatable part.

4. Structure as set forth in claim 1 in which one of said surfaces is smooth and the other is comb-like.

5. Structure as set forth in claim 1 including locking means to hold the parts in selected relative positions.

6. Structure as set forth in claim 1 in which one of the parts is cylindrical and is provided with grooves to form one of the nap-engaging surfaces.

7. A suction cleaner nozzle having a convexly formed nap-engaging surface portion provided with narrow longitudinal and transverse grooves, and so arranged that air entering the nozzle will be drawn thereunder, said convexly formed nap-engaging portion being so constructed that the object cleaned is protected from the cutting effect of the groove edges.

8. A suction nozzle including a hollow member having an elongated suction opening bounded by lips having surface contacting faces, one of said lips including a rotatably mounted cylindrical rod, one side of said rod being smooth and the other side being formed with a plurality of transverse grooves, said rod being formed with a slot extending diametrically therethrough, and a locking member pivotally mounted in said slot.

9. A suction nozzle including a hollow member having an elongated suction opening bounded by lips having surface contacting faces, one of said lips including a rotatably mounted cylindrical rod, one side of said rod being smooth and the other side being formed with a plurality of transverse grooves, said rod being formed with a slot extending diametrically therethrough, and a locking member pivotally mounted in said slot, said locking member being formed with a handle part disposed permanently outside said slot and another part pivotal from within to outside said slot for locking said rod against rotation.

10. A suction nozzle including a hollow member having an elongated suction opening bounded by lips having surface contacting faces, one of

5 said lips including a rotatably mounted cylindrical rod, one side of said rod being smooth and the other side being formed with a plurality of transverse grooves, said rod being formed with a slot extending diametrically therethrough, and a locking member pivotally mounted in said slot, said locking member resiliently engaging the sides of said slot.

10 11. A nozzle including bounding walls forming a suction passage, one of said walls having a first set of downwardly projecting lugs convexly rounded on faces toward the nozzle passage and relatively straight on faces opposite the nozzle passage and a second set of lugs in alignment 15 with the first-mentioned lugs with reference to

the normal direction of movement of the nozzle, the lugs of the second set being convexly rounded on faces opposite the nozzle passage and relatively straight on faces toward the nozzle passage, the relatively straight faces being close together, whereby on forward or backward movement of the nozzle the lugs having rounded faces forward act as guards with respect to the relatively straight faces.

12. A surface engaging lip structure for a suction cleaner nozzle having a generally semi-cylindrical nap engaging surface traversed by a multitude of transverse grooves intersected by a narrow longitudinal groove at the bottom portion.

GEORGE HORACE CRANMER. 15
